UNITED STATES PATENT OFFICE.

CHARLES A. CONKLIN, OF ADRIAN, MICHIGAN.

COFFIN-FASTENER.

SPECIFICATION forming part of Letters Patent No. 443,822, dated December 30, 1890.

Application filed May 8, 1890. Serial No. 351,043. (No model.)

To all whom it may concern:

Be it known that I, CHARLES A. CONKLIN, a citizen of the United States, residing at Adrian, in the county of Lenawee and State of Michigan, have invented certain new and useful Improvements in Spring Locking Devices for Burial-Casket Caps or Lids; and I do hereby declare the following to be a full, clear, and exact description of the invention, such as will enable others skilled in the art to which it appertains to make and use the same.

My invention relates to improvements in spring locking-catches for caps or lids of burial-caskets adapted to be concealed within the lid and operated by means of a projecting lever so arranged that the cap or lid will be secured by simply pushing the same down, and when desired the catch may be released by means of the projecting lever.

The object of my invention is to provide a catch which may be used with any of the present well-known forms of caps or lids for burial-caskets.

Said invention consists in certain novelty in the construction, arrangement, and combination of the various parts of the same, all of which I will now proceed to point out and describe, reference being had to the accompanying drawings, in which—

Figure I is an enlarged longitudinal central section of the locking device, showing the same attached to the cap or lid and in position it assumes when locked, dotted lines indicating position of lever and catch when released, the lever being drawn up. Fig. II is a perspective of the device removed from the cap or lid; Fig. III, a side elevation partially broken away, the operating-lever being drawn down to release the catch, instead of up, as in Fig. I.

Referring to the drawings, A indicates the cap or lid of a burial-casket, which is secured over the glass head-plate; B, the glass plate, and C the end of the head of the main lid of the casket, said parts being partially broken away.

The lower end of the cap or lid A is secured to the main lid of the coffin by hooks or any other well-known means, which is not necessary to describe, as it forms no part of the present invention. The forward end of the

cap or lid is recessed at a at about the center, and is provided with a slot a', extending from said recess to the edge of the cap. The locking device is secured within said recess, and consists of a plate D, preferably of circular form, let into the recess, so that its lower surface will be flush with the bottom of the lid. Said plate may be secured to the lid by screws 55 or in any other suitable manner. The plate is provided with a substantially rectangular recess or opening d, and upwardly-projecting bearings d' at each end of said opening.

E is the locking-bolt, having its shank 65 mounted in said bearings and provided with a downward projection E', on the outer edge of which are formed locking spurs or notches e, having their under sides beveled. Any desired number of spurs or notches may be used. 70 In the drawings I show but two.

e' is a shoulder on the end of the bolt above the locking-spurs, and e² is a projection extending above said bolt. The forward portion of said bolt is located in a radial slot d² 75 in the plate.

F is a guard or shield surrounding the projection E', the locking-spurs normally projecting beyond the outer side of said guard. The guard F is secured to the plate by means of 80 flanges f riveted to said plate, and is provided with upwardly-extending lugs f' on each side of the radial slot d².

G is a double-acting operating-lever pivoted or fulcrumed to said lugs by a suitable pin g. 85 Said lever has an upward projection G' engaging the upper projection e² of the locking-bolt, and a projection or shoulder G² engaging the shoulder e' on the end of said bolt, said lever thus having projections on each 90 side of its fulcrum, enabling it to be moved up or down to operate the bolt and forming a double-acting lever.

H is a spiral spring surrounding the shank of the bolt, one end of said spring resting 95 against the rear bearing of the shank and the other end engaging a pin h in said shank. This spring serves to hold the bolt forward, so that the locking-spurs normally project beyond the guard in position to engage the locking-shoulder i, which is formed in the end of the main lid of the coffin, said shoulder preferably being formed of a metal plate secured over a recess in said end of the main lid. 100

When the casket and cap or lid is covered with cloth, the lever projects from the end of the said cap and guard, and the locking-spurs or catch portion of the bolt alone project 5 through said cloth on the under side of the lid. When the lid is closed and pushed down, the beveled edges of the spurs engage the upper side of the locking-shoulder *i* and are forced back. As said spurs pass the shoulder 10 the spring throws the bolt forward, causing the catch or spurs to engage. By providing the bolt with two or more locking-spurs it is enabled to accommodate itself to different thicknesses of cloth which may be used in 15 covering the casket, or to any imperfections in finish and fitting.

The lever is provided with an operating-cord *K*, attached to the eye *K'* in the end of same, and said lever being double-acting, the 20 bolt may be released by drawing the lever up or down, thus enabling the device to be used with any of the well-known forms of caskets.

L indicates the cloth covering of the lid and casket.

25 Having thus fully described my invention, I claim as new and desire to secure by Letters Patent—

1. A spring-catch for burial-casket caps or lids, comprising a plate secured to the under

side of the forward end of the cap or lid, a 30 spring-actuated bolt mounted in bearings secured to said plate and provided with a downwardly-extending projection having a series of locking-spurs adapted to engage a locking-shoulder in the casket, and a lever fulerumed 35 upon said plate and engaging the bolt to release the locking-spurs from the locking-shoulder, substantially as shown and described, for the purpose set forth.

2. A spring-catch for burial-casket caps or 40 lids, comprising a plate secured to the under side of the forward end of the caps, a spring-actuated bolt mounted in bearings secured to said plate and provided with a downwardly-extending projection having a series of lock- 45 ing-spurs adapted to engage a locking-shoulder in the casket, and a double-acting lever fulerumed upon said plate and engaging the bolt to release the locking-spurs from the locking-shoulder, substantially as shown and 50 described, for the purpose set forth.

In testimony whereof I affix my signature in presence of two witnesses.

CHARLES A. CONKLIN.
